Application March 17, 1939, Serial No. 262,572

8 Claims. (Cl. 264—3)

This invention relates to a governor for regulating the speed of a prime mover or mechanism driven thereby and has more particular reference to governors in which the speed regulator is operated by a servo motor actuated by pressure fluid.

The general object of the invention is to provide a governor of the above character which is simple and inexpensive in construction, which is extremely sensitive to speed changes, which will maintain a selected speed within very close limits, and which may be adapted readily to a wide variety of different locations and types of mountings.

Another object is to improve the speed regulation of such a governor by providing for automatically varying the amount of speed droop which is effective under different load conditions.

A further object is to provide a novel means for facilitating adaptation of the governor for operation of its driving member in either direction.

The invention also resides in certain novel structural characteristics which facilitate carrying out the foregoing objects and contribute to the simplicity of the governor construction and reliability of operation.

Other objects and advantages of the invention will become apparent from the following detailed description taken in connection with the accompanying drawings, in which

Figure 1 is a perspective view of the improved governor.

Fig. 2 is a vertical diametrical section.

Figs. 3 and 4 are sectional views taken respectively along the lines 3—3 and 4—4 of Fig. 2.

Fig. 5 is a fragmentary perspective view of certain of the operating parts in a modified form of the governor.

Fig. 6 is a fragmentary horizontal sectional view of the modified governor.

Fig. 7 is a fragmentary sectional view of the throttle rod shown in Fig. 5.

Fig. 8 is a diagrammatic view showing the range of throttle movement.

Fig. 9 is a characteristic speed droop curve of the governor.

While the invention is susceptible of various modifications and alternative constructions, we have shown in the drawings and will herein describe in detail the preferred embodiment. It is to be understood, however, that we do not intend to limit the invention by such disclosure but aim to cover all modifications and alternative constructions falling within the spirit and

scope of the invention as expressed in the appended claims.

The governor shown for purposes of illustration is especially adapted for regulating the speed of an internal combustion engine and for this purpose is usually supported at one side of the engine on an adapter 10 through which is extended a mechanical connection including a shaft 11 for driving the governor in synchronism with the engine being governed. In the present instance, the speed of the engine is regulated by endwise shifting of a rod 12 leading to the engine throttle and actuated by the governor. Preferably, the latter is supplied with actuating fluid delivered through a conduit 13 from an external source of supply such as the lubricating system of the engine.

The main operating parts of the governor are housed in a casing 14 the lower end of which is bolted to the adapter 10 and spaced therefrom by a plate 15. The casing is open at its enlarged upper end 16 and carries a tubular extension or cap 17 closed by a cover 18.

Speed changes of the engine are detected in the usual way by upstanding inertia weights or flyballs 21 pivoted on horizontal pins 22 on a head 23 which rests on a ledge 24 and is integral with the upper end of a sleeve 25 journaled in a vertical bore 26 in the lower portion of the casing 14. The lower end of the sleeve has a spline connection 27 with a coupling 28 pinned to the upper end of the drive shaft 11. A collar 29 is forced onto the lower end of the sleeve to hold the latter against withdrawal. Integral with the flyballs 21 are horizontal arms 29 which bear upwardly against the lower race ring 31 of a thrust bearing having antifriction elements or balls 32 disposed between the ring 31 and an upper ring 33. The latter abuts against a flange or shoulder 34 on a rod 35 reciprocable in the bore 36 of the sleeve 25 and carries an enlarged head or piston 37 at its lower end cooperating with ports 38 in the sleeve 25 to form a control valve. Preferably, the diameter of the ports is a few thousandths of an inch less than the length of the piston 37.

The valve functions to control the flow of pressure fluid or oil through a groove 39 around the sleeve and a passage 41 to and from the lower end of a vertical cylinder 40 bored in the casing 14. A piston 42 reciprocates in the cylinder and cooperates therewith to form the servo motor for actuating the throttle control rod 12. When the valve member 37 is positioned as shown in Fig. 2, the ports 38 are covered and the fluid is held in

the cylinder. Raising the valve member above or lowering it below this position connects the lower and upper parts of the sleeve bore 38 to the passage 41 through the ports 38 and the groove 39, thereby respectively permitting fluid to drain from and admitting fluid under pressure to the cylinder 40. Fluid escaping through the lower end of the sleeve flows through openings 50 in the coupling 28 and drains through the adapter 10 back to the engine crank case or sump. Leakage through the valve parts into the upper part of the casing 14 is similarly returned to the sump through a passage 60.

To simplify the motion transmitting connection, the flat upper end of the piston 42 has a 15 rolling and bearing contact with a rounded surface 43 on the free end of a crank 44 fast on the inner end of a rockshaft 45 (see Fig. 4) which is journaled in a bushing 46. The bushing projects through and threads into a side wall of the casing. On its outer end, the rockshaft carries an arm 47 pivotally connected by a pin 47^a to one 20 end of the throttle rod 12 and carrying a head which abuts against one end of a spring 48 coiled about the rod. The other end of the spring bears 25 against a stop 49 on the casing and acts in compression so as to urge the throttle rod to the left as viewed in Fig. 2, thereby tending to reduce the speed of the prime mover. The extent of 30 throttle opening may be limited by an adjustable stop screw 51 threading into a lug 52 in the cap 18 and positioned to limit the upward movement of the arm 47. In the "off" position of the throttle, the piston rests against the lower end of the cylinder 40.

While for some applications the pressure developed in the lubricating system of the engine is sufficient to enable the throttle to be actuated with the required rapidity, it is preferred to employ fluid at higher pressure supplied by a booster pump incorporated in the governor. The pump shown is of the gear type comprising gears 53 and 54 disposed in a recess 55 formed in the plate 15 and closed by the bottom of the casing 14. The gear 53 rotates on a stud 56 while the gear 54 is splined on the lower end of the sleeve 25.

Opposite sides of the pump chamber 55 communicate with vertical passages 57 and 58 (Fig. 3) which constitute the pump inlet and outlet depending on the direction of rotation of the gears. At their upper ends, these passages connect with a transverse bore or passageway 59 extending completely through the casing 14 with its opposite open ends similarly threaded. At the intersection of the two bores 28 and 59, the valve sleeve 25 is formed with an annular groove 61 connected by ports 62 to an elongated groove 63 defined between the internal wall of the sleeve and a narrowed portion 64 of the valve plunger 35. In this way, both of the passages 57 and 58 communicate with each other at all times and with the interior of the sleeve above the valve piston 37.

The end of the bore 59 which communicates with the passage that is to be the pump outlet as determined by the direction of rotation of the drive shaft 11 is closed by a plug 65 which is threaded to render it removable. A sleeve 66 screwed into the other similarly threaded end of the bore 59 is connected externally of the casing to the fluid supply line 13. The inner end of this sleeve is received snugly in the bore 59 beyond the passage 58 and has ports 67 and 68 spaced along its length. Through a passage 69, the port 68 establishes constant communication

between the fluid supply line 13 and the passage 58 which in this instance constitutes the pump inlet.

Slidable within the sleeve 66 is a valve member 71 urged toward a cross pin 72 by a compression spring 73 disposed within the sleeve. With the member 71 positioned as shown in Fig. 3, the port 67 is closed. In response to a pressure build up in the pump outlet and the supply passage leading to the control valve 37, the member 71 will move to the left, uncovering a portion of the port 71 proportional to the pressure increase, thereby permitting fluid to be by-passed from the pump outlet to the pump inlet around the valve sleeve 25 through the passage 59 which therefore serves as a by-passage as well as part of the pump outlet and the fluid intake. In this way, the valve member 71 operates automatically to maintain a pressure of the fluid supplied to the pilot valve predetermined by the stress of the spring 73.

It will be observed that the by-pass valve is self-contained within the threaded sleeve 66 and that the latter is mountable interchangeably in either end of the bore 59 so as to thereby adapt the governor for proper operation regardless of the direction of rotation of the drive shaft 11 which will vary with different installations. By removing the plug 65 and replacing it by the sleeve 66, fluid will be directed properly to and from the pump and to the pilot valve and will be by-passed properly when the shaft 11 is driven in a direction to cause the pump to withdraw fluid from the passage 57 and deliver 35 the same to the passage 58. The governor may thus be adapted for reverse rotation of the shaft 11 simply by reversing the positions of the plug 65 and the sleeve 66 in the bore 59. In such a case, the fluid flow would be to the pump through the sleeve 66 and the passage 57, the fluid being delivered to the valve through the passage 58.

The tendency of the flyballs 21 to move outwardly and lift the pilot valve rod 35 is counteracted by a speeder spring 74 of frusto-conical shape acting between the valve rod and a cross head 77 which serves as a guide for the upper end of the speeder spring. Herein, the larger end of the speeder spring is seated on a washer 75 received on the upper end of the rod 35 above the flange 34. With this arrangement, assembly of the parts is facilitated since the force of the speeder spring acting through the medium of the flange 34 effectually holds the parts together at all times. The upper end of the speeder spring receives and bears against a shoulder 76 on the cross head 77. The latter is of inverted U-shape (see Figs. 3 and 4) with its legs 78 slidably in internal ways 79 formed in opposite walls of the casing 14 and extending parallel to the axis of the pilot valve and flyball head.

Adjustment of the stress under which the speeder spring is maintained may be controlled from a point outside of the governor casing as 65 by shifting a hand lever 81^a held in different positions by a detent 81^b coaxing with a quadrant 81^c. The lever is connected to an external control rod 81 pivotally connected to an arm 83 on a rockshaft 84 which is journaled in a sleeve 85 screw threaded into the upper end portion of the casing 14. Fast on the inner end of the rockshaft is a crank 86 pivotally connected at 87 to one end of a lever 88 which overlies the cross head 77 and has a curved surface 89 intermediate its ends bearing downwardly against the upper

surface of the cross head. The opposite end of the lever 88 is slotted as indicated at 81 to receive a fulcrum pin 92 which is mounted in a manner later to be described.

For any given position of the fulcrum pin 92, shifting of the rod 81 in opposite directions will, through the medium of the cranks 73 and 86, raise and lower the pivot 87, thereby swinging the lever 88 about the fulcrum 92 to increase and decrease the counteracting force exerted by the speeder spring. To enable the prime mover to be shut down by manipulation of the speed adjusting lever 81^a, a head 93 is formed on the upper end of a rod 94 which is loosely received at its lower end in the upper end of the valve rod and held therein by a cross pin 95. A lost motion connection is thus provided between the lever 88 and the valve rod so that by raising the pivot 87 above the normal range through which it is shifted to adjust the speeder spring, the lever 88 encounters the stop 93, thereby enabling the valve rod to be lifted positively to the shut down position.

When the prime mover being controlled is operating at the speeds determined by the setting of the speeder spring, the valve parts will be positioned as shown in Fig. 2, the valve piston 37 completely covering the ports 38 so that there is no flow of fluid either to or from the servo cylinder. All of the fluid delivered by the pump will then be by-passed through the sleeve 66 and the part 71 back to the pump inlet. In response to a decrease in speed, the flyballs will move inwardly lowering the pilot valve member 35 and uncovering the ports 38 to pass fluid to the servo cylinder. The resulting pressure increase lifts the piston 42 and results in shifting the throttle rod 12 in the opening direction until the speed decrease has been corrected. When the engine speed increases, the flyballs move outwardly lifting the valve rod and connecting the passage 41 to the lower end of the sleeve bore 33. The resulting flow of fluid from the cylinder 40 under the action of the spring 48 permits the piston 42 to be lowered, the throttle being thereby shifted to the left to decrease the fuel supply.

To avoid hunting during correction for a speed change, provision is made for adjusting the speeder spring automatically so as to produce speed droop, that is, to proportion the amount of correction in accordance with the speed deviation. This is effected in the present instance by swinging the lever 88 about the pivot 87 as a fulcrum in response to movement of the crank arm 44 by the servo motor. In the form shown in Figs. 2, 3, and 4, the fulcrum pin 92 is mounted on the depending arm of a bellcrank 96 pivoted at 97 on a lug upstanding from the crank arm 44. Pivoted on the bellcrank 96 at a point 98 spaced from the pivot 97 is a link 101 which hangs downwardly and is pivotally connected to an eccentric pin 102 on a shaft 103. The latter is journaled in a sleeve 104 threaded into the casing 14 to locate the axis of the shaft 103 coincident with the axis of the rockshaft 45. On its outer end, the shaft 103 carries a manually operable knob 105 which may be turned to vary the position of the pin 102. Each selected setting of the knob is maintained frictionally by the action of a spring 106 which urges the knob against the outer flanged end of the sleeve 104.

It will be apparent that for any fixed position of the pin 102, the bellcrank 96 will transmit the motion of the crank arm 44 to the slotted end of

the lever 88. Since the pin 102 is offset slightly from the center of the crank arm 44, a slight movement of the pin 92 radially of the arm 44 may occur during movement of the arm, but this change in the position of the pin 92 is too small to be of material consequence. Through the action of the link 101 and the adjusting pin 102, the motion transmitting ratio of the linkage is varied over a considerable range in the adjustment of the pin 102 from its upper to its lower dead center positions. During such adjustment, the pin 92 is moved along the slot 81. As a result of this adjustment of the motion transmitting ratio, the amount of speed droop produced by the linkage will be varied correspondingly.

By interposing the link 101 between the eccentric pin 102 and the lever 96, provision is made for mounting the speed droop adjusting shaft 103 and the throttle actuating shaft 45 on a common axis. The sleeves 46 and 104 thus may be adapted for mounting interchangeably in the threaded bores on either side of the casing, thereby enabling the positions of the throttle rod and droop adjuster to be reversed relative to the governor casing as may be required in order to adapt the governor to different installations. In making such reversal, the only part required to be changed is the crank 44.

For a similar reason, a threaded bore 107 (Fig. 4) of the same size as the bore in which the sleeve 85 is screwed is formed in the side of the casing 14 opposite the sleeve and in axial alignment therewith. This bore 107 is closed by a plug 108 which may be removed and replaced by the sleeve 85 when the engine environment requires that the speeder spring adjustment be placed on the opposite side of the governor.

To explain the action of the speed droop mechanism, let it be assumed that the lever 81^a and the knob 105 are positioned to establish the desired engine speed and droop. As a result, the fulcrum pins 87 and 102 are stationary, the lever 88 thus being adapted to swing about the then fixed pin 87 in unison with the arm 44 to which the lever is connected as above described by the bellcrank 96. In response to an increase in the speed of the engine, the valve rod 35 will be raised against the action of the speeder spring partially uncovering the ports 38 and permitting fluid to flow from the cylinder 41 and the piston to be lowered by the throttle spring 48. In this movement, the pivot 87 is lowered with the crank arm 44 and, through the medium of the bellcrank 96, correspondingly lowers the free end of the lever 88. As a result of this, the cross head 71 is lowered and the stress of the speeder spring increased and the governor thus conditioned for maintaining a slightly higher speed. The droop thus produced in the speed setting is approximately proportional to the movement of the servo piston 42 and therefore the speed change causing the change in throttle setting.

In a similar way, the setting of the speeder spring is changed in the reverse direction in response to a decrease in engine speed which results in lowering of the valve member 37 and the admission of fluid to the cylinder. As the piston 42 rises, the bellcrank lever 96 raises the lever 88. This results in decreasing the speeder spring stress in proportion to the speed decrease.

To provide for greater stability in the control of the prime mover under all load conditions, the invention provides for a greater amount of effective speed droop under light loads than under heavy loads thereby compensating for the inher-

ently greater acceleration possessed by the prime mover when operating under lighter loads. This may be accomplished through the provision of means which operates with changes in the position of the servo piston and therefore the load condition to produce a greater deflection of the speeder spring for a given change in the position of the throttle rod 12 under light loads than under full loads. This modifying action may be produced either in the motion transmitting mechanism leading to the throttle or in the speed droop linkage itself. The former method is preferably employed.

In the present instance, the speed droop linkage is constructed so that its leverage remains substantially constant for a given speed droop setting and modification of the speed droop curve is produced in the throttle actuating mechanism. To this end, the crank arm 47 is mounted on its rockshaft 45 to swing through an arc *a* during movement of the throttle rod between idle and full load positions indicated in Fig. 8 which arc is disposed between the horizontal and vertical positions of the crank arm. Usually, the crank arm is arranged to overtravel in opposite directions beyond this arc so as to provide for engine shut-down and a reserve fuel supply for abnormal loads, the crank moving through an arc *b* determined by the limiting movements of the servo piston 42.

Owing to the location of the arc *a*, the throttle movement produced by a given movement of the servo piston 42 will equal the projection of the corresponding travel of the crank pin 47^a on the line of reciprocation of the throttle rod. Thus, a somewhat greater movement of the servo piston will be required to produce a given travel of the throttle rod when the crank 47 is near the no load position than when the engine is operating near full load. Since the adjustment of the speeder spring 14 to produce speed droop results from movement of the throttle rod, the change in leverage thus obtained is reflected in a change in the effective speed droop under different load conditions. That is to say, for a given movement of the throttle rod, there will be a greater movement of the cross-head 17 and a greater change in the speeder spring adjustment when the throttle is positioned for operation of the engine under light load than when the throttle is near its maximum load position. This will be apparent from Fig. 9 which shows a characteristic speed droop curve *e* of the present governor shown in Fig. 9, when used in connection with one form of Diesel engine with a five per cent speed droop setting. It will be observed that the engine speed is a non-linear function of the load. Thus, at light loads, the slope of the curve and therefore the effective speed droop is greater as indicated by the tangent line *c* than at heavy loads as indicated by the line *d*. In the illustration given, the effective droop at the idle speed setting is approximately sixty per cent greater than at the full load setting.

By regulating the effective speed droop in this manner, the increased tendency toward hunting during operation of the engine under light loads when its acceleration is greatest is overcome effectually. Greater stability in the operation of the engine and closer regulation of its speed are thereby obtained. As a result, it is possible with the present governor to control the operation of one commercial Diesel engine with a total speed droop as low as 0.66 per cent.

Fig. 5 illustrates a modification of the throttle

actuating mechanism in which the throttle rod 12 is extended through the upper casing section 17 and slidable endwise therein. The rod is urged toward off position by a compression spring 111 acting on a collar 112 fixed to the rod. A compression spring 113, stronger than the spring 111, acts between the collar and a block 114 rigid with one end of a sleeve 115 encircling the rod 12 between the block and a nut 116 by which the position of the block along the rod may be adjusted to change the maximum throttle opening produced by the governor. The block constitutes the follower for a bifurcated cam 117 in the form of an arm cast integral with and upstanding from the crank 44 previously referred to. The cam has convexly curved surfaces 118 normally bearing against the block 114. In this instance, the crank 44 rocks on the stud 130 supported by a plug 131 threading into the casing 14.

The foregoing arrangement permits of overriding the governor manually either to increase or decrease the fuel supply. By pressing on a knob 119, the spring 111 may be overcome and the throttle opened independently of the governor. When the knob is pulled with a force sufficient to compress the spring 113 against the action of an hydraulic servo motor, the throttle will be moved to the left to decrease the fuel supply.

In this form, the speeder spring adjusting rock-shaft 84 is journaled in and projects from a sleeve 120 which in turn is adapted to rock in a bushing 121 threaded into the casing 14. Fast on the inner end of the sleeve is a crank 122 connected to one end of a rod 123 the other end of which carries a pin 124 projecting through and slidable along the slot 91 in the spring adjusting lever 88. The pin carries a roller 125 riding in a straight groove 126 in the operating crank 44. The outer end of the sleeve 120 has fast thereon a segment 127 which may be adjusted angularly to shift the fulcrum pin 124 back and forth along the slot 91. The selected speed droop adjustment thus produced is maintained by a set screw 128 threaded into the casing through a slot in the segment 127.

By virtue of its connection through the medium of the roller 125 and pin 124 with the main actuating lever 44, the lever 88 swings about the pivot 87 with changes in the position of the servo piston producing speed droop in the manner previously described. The effective mechanical advantage of the lever will be increased and decreased as the pin 124 is shifted outwardly and inwardly along the slot 126 thereby respectively increasing and decreasing the amount of inherent speed droop that will be produced.

As in the governor first described, provision is made for varying the movement imparted to the throttle 12 for a given increment of servo piston movement in different parts of the operating range so as to produce a characteristic speed droop curve of the character shown in Fig. 9. This may be accomplished simply and conveniently by shaping the cam surfaces 118 as shown in Fig. 7. At or near the shut off position shown in full lines, the cam produces a less throttle movement and therefore more effective speed droop for a given load or throttle change than is produced under full load as shown in dotted outline.

We claim as our invention:

1. In a fluid actuated governor, the combination of a hollow casing, a fluid control valve within said casing having an endwise shiftable

member, a head rotatable in said casing around the axis of said member and carrying flyballs connected to the member, a coiled speeder spring connected at one end to said member and acting to oppose said flyballs, parallel slideways formed in opposite walls of said casing and extending parallel to said member, a cross head slidable in said ways and connected to the other end of said spring to form a guide therefor, and means for adjusting the position of said cross head to vary the stress of said spring.

2. In a governor, the combination of a valve having a rod shiftable axially in response to changes in the speed of a rotary member, a coiled compression spring urging said rod in one direction, a floating lever bearing intermediate its ends against said spring, a crank arm on one side of said rod connected at its free end to one end of said lever and adjustable to vary the stress of said spring, a second crank arm on the opposite side of said rod, a servo motor controlled by said valve and actuating said second crank arm, means pivotally connecting the other end of said lever and said second crank arm including a pin and slot connection, and means for manually adjusting the position of the pivot pin along its slot.

3. In a governor, the combination of a valve having a rod shiftable axially in response to changes in the speed of a rotary member, a coiled compression spring urging said rod in one direction, a floating lever bearing intermediate its ends against said spring and having fulcrums at either end, manually operable means for adjusting one of said fulcrums to vary the stress of said spring, a servo motor controlled by said valve, a motion transmitting connection between said element and said other fulcrum permitting of adjustment of the latter along the lever to vary the speed droop characteristic of the governor, and means for manually adjusting the position of said last mentioned fulcrum.

4. In a governor, the combination of a valve having a rod shiftable axially in response to changes in the speed of a rotary member, a speeder spring urging said rod in one direction, a floating lever swingable about first and second fulcrums to adjust said spring, means for shifting one of said fulcrums to change the speed setting of said spring, a servo motor controlled by said valve and moving said other fulcrum to actuate said lever automatically and produce speed droop, and means for manually adjusting said last mentioned fulcrum independently of said servo motor.

5. In a governor, the combination of a valve having a rod shiftable axially in response to changes in the speed of a rotary member, a speeder spring urging said rod in one direction, 10 a floating lever swingable about first and second fulcrums to adjust said spring, means for shifting one of said fulcrums to change the speed setting of said spring, and a servo motor controlled by said valve and moving said other fulcrum to actuate said lever automatically.

6. In a governor, the combination of a valve having a rod shiftable axially in response to changes in the speed of a rotary member, a speeder spring urging said rod in one direction, 15 a lever for adjusting said spring, a servo motor controlled by said valve and having a movable element, a second lever for communicating the movements of said element to said first lever, said second lever having a shiftable fulcrum, and means for manually adjusting said last mentioned fulcrum independently of said servo motor.

7. In a governor, the combination of a valve having a rod shiftable axially in response to 20 changes in the speed of a rotary member, a coiled compression spring urging said rod in one direction, a floating lever bearing intermediate its ends against said spring and having fulcrums at opposite ends, one being fixed and the other being shiftable longitudinally of the lever, a servo motor controlled by said valve and having a movable element connected to said shiftable fulcrum to produce speed droop, two concentric rockshafts, a crank on one of said shafts supporting said fixed fulcrum and adjustable to vary the speed setting of said spring, a crank on the other rockshaft connected to said shiftable fulcrum and adjustable to shift the latter along said lever.

8. In a governor, the combination of a speed responsive valve having a movable member, a speeder spring urging said member in one direction, two rockshafts arranged coaxially in end to end relation, a servo motor controlled by said valve and adapted to rock one of said shafts back and forth, a lever system for transmitting the motion of said first shaft to said speeder spring, said system including a floating fulcrum, and means connecting said fulcrum and said other rockshaft to permit of adjustment thereof by rocking of the shaft.
